UNITED STATES PATENT OFFICE

143,323

DESIGN FOR A RAILWAY CAR BODY

George A. Jergenson, Detroit, Mich., assignor to
General Motors Corporation, Detroit, Mich., a
corporation of Delaware

Application May 7, 1945, Serial No. 119,443

Term of patent 14 years

(Cl. D66—1)

To all whom it may concern:

Be it known that I, George A. Jergenson, a citizen of the United States and a resident of Detroit, county of Wayne, State of Michigan, have invented a new, original, and ornamental Design for a Railway Car Body, of which the following is a specification, reference being made to the accompanying drawing forming a part thereof.

In the drawing:

Fig. 1 is a side elevational view of a railway car body, showing my design.

Fig. 2 is a plan view of the car body.

Fig. 3 is an elevational view, taken from the right-hand side of Fig. 1, and showing the rear end of the car body.

The appearance of the side of the car body opposite to that shown in Fig. 1 is substantially the same as that shown in Fig. 1, and the appearance of the end of the car body opposite to that shown in Figure 3 is conventional.

I claim:

The ornamental design for a railway car body, substantially as shown and described.

GEORGE A. JERGENSON.
